UNITED STATES PATENT OFFICE

1,999,898

THERMOSTATICALLY CONTROLLED
CURLING IRONMaurice F. Fitzgerald, Winsted, Conn., assignor
to The Fitzgerald Manufacturing Company,
Winsted, Conn., a corporation of Connecticut

Application July 12, 1932, Serial No. 622,126

3 Claims. (Cl. 219—24)

This application relates to improvements in curling irons.

One of the features of the present invention is the construction and arrangement of a curling iron combining an electrical heater element and a thermostatically operated switch for controlling the supply of current to the heating element.

Another feature of the present invention relates to improvements in the assemblage of a curling iron in conjunction with a thermostatic switch whereby a simple and compact arrangement is provided, and the thermostatic element is so positioned that it accurately determines the heating effect applied to the hair-engaging and waving structures.

Other features of the invention will appear in the course of the following specification and claims, and are shown on the accompanying drawings, in which:

Figure 1 is a side elevation of a curling iron according to the present invention.

Figure 2 is a plan view of the same.

Figure 3 is a longitudinal section substantially on the line 3—3 of Figure 2.

Figure 4 is a detail view of the thermostatic control elements, on a larger scale, substantially on line 4—4 of Figure 1.

Figure 5 is a transverse section substantially on line 5—5 of Figure 4.

Figure 6 is a perspective view of the thermostatic switch assembly.

In these drawings, the curling iron is illustrated as having three relatively movable members comprising a body 10, the tongs 11 and the slider 12. The body 10 is provided with transverse ribs establishing grooves for the reception of strands of the hair. The tongs 11 are formed in this illustrative form of a single strip of metal which has parallel portions at its ends spaced from the body 10 and adapted to be rocked about the pivot 13 for holding the hair in the aforesaid grooves of the body 10. The slider 12 extends over the body and tong arms, and is provided at its edges with the teeth 12a for engaging the strands of hair and moving them lengthwise with respect to the ribs of the body whereby to produce a distortion or curling of the hair in two directions.

The body 10 is of relatively thick material, and thus serves as a heat accumulator so that its temperature does not change rapidly. It has a central trough or cavity in which is located the electrical heater element 14. A cover piece 15 rests within the upper portion of the body 10 to hold

the heater element 14 in position. The slider 12 is provided with a slot 12b through which may be passed a screw 16 having a collar thereon for binding and holding the cover 15 in position, and for permitting the slider 12 to move lengthwise of the body. 5

At its rear end, the body is provided with an upward extension having inclined surfaces 10a between which is received the angularly bent portion 15a of the cover 15 (Fig. 3), which thus 10 serves to protect the conductors running from the heater element 14 to the thermostatic switch.

Within the cavity of this upwardly extending portion is positioned an insulating block 16 forming a support for the thermostatic switch elements. A substantially rigid stationary blade 17 has a stationary contact 18 on the end thereof. A flexible bi-metallic blade 19 has a cooperating contact 20. These two blades are received in grooves of the block 16, and a screw 21 passes 15 through the same and through insulating washers 22 and collars 23 which prevent the conduction of current to the body, tongs or slider. This screw 21 likewise passes through the wall of body 10, a spacer 24 being interposed, and is held fixed 20 25 so that the block is immovable, by means of a clamping nut 25 outside of the body 10.

The free end of the bi-metallic bar 19 is bent over and a strip of insulating material 26, such as mica, is positioned against it and projects laterally beyond its end. A metal sleeve or clip 27 is folded around this bent end and mica strip to hold the same fixedly together. 30

To the opposite side wall of the body 10 is fixed a regulator blade 28 which is held in position by 35 a small bolt 29, and may be varied in position by the adjusting screw 30 having a lock nut 31, so that the engagement with its free end of the mica strip 26 whereby to determine the temperature at which the thermostatic device will operate for separating the contacts 18, 20. 40

One conductor 32 leads from a source of current to the heater element 14, while the return conductor 33 from the heater element is connected to one of the thermostat blades, for example, to the bi-metallic blade 19. The other blade in such example, the stationary blade 17, is connected by conductor 34 back to the source. A hood 35 is provided for cooperation with the body 10 and the cover end 15a to protect the thermostatic members against accidental contact or derangement. This hood fits against the walls of the upward extension of the body 10 and against the inclined surface 10a thereof so that the conductive cable cord to the device is di- 50 55

rected backward toward the handle, but at an angle thereto, so that the conductor cord does not tend to engage the heated portions, nor to become entangled with the hair.

- 5 In this illustrative form, the slider 12 is moved by a slider lever 42 which is mounted by a pivot 43 on the body arm 44 which is fixedly connected to the body 10, so that there is no relative movement of the slider lever and slider while the tongs 10 are being closed upon the body. The end of the slider lever is connected by a link 45 with the slider member, so that the latter may be operated thereby and without contact of the hand with the heated slider 12.

15 For greater facility and operation, and for easy manufacture, the tongs 11 which are formed as indicated above of a single strip of metal, have the two arms thereof approximated adjacent the pivot 13 and then extend rearwardly and into 20 a heat insulating handle 50, being curved relatively downward close to the handle, so that the handle axis is at an angle to the tongs.

25 By particular construction shown, the provision in the trough open at the top of the body 10 for the reception of the heater element 14, and the upward extension of this body with the cavity in extension of the trough, permits a simple and easy assemblage of the heater element and its conductors 32, 33, and the enclosure of these 30 parts by the cover 15 and the bent end 15a. The space afforded by the upward extension is contiguous to a heated portion of the body 10, and also permits an installation of a thermostatic switch of ample size for continued service. The 35 hood which completes the closure of the upward extension of the body 10 surrounds the free ends of the bi-metallic blade 19 and the stationary blade 17 so that these elements are supported in a heated zone, but at a sufficient distance from the heater element 14 proper, so that they operate 40 according to the temperature of the body 10 and not of the heater element.

The illustrated form likewise employs an open-ended slot 12c on the slider 12 which fits around the extension of the body, being received in grooves 19b thereof, so that the slider is positively guided at both ends, i. e. at the tip by the head or screw 16 in its engagement in slot 12b, and at the heel end by the engagement in the grooves 19b.

It is obvious that the invention is not limited solely to the form of construction shown, but that it may be modified within many ways of the scope of the appended claims.

55 Having thus described the invention, what I claim as new and desire to secure by Letters Patent, is:—

1. A curling iron comprising an elongated trough-like body having an electrical heater ele-

ment therein, a handle joined to one end of said body, tongs pivotally mounted for movement with respect to said body, an angular extension from said body adjacent the handle end and having a groove constituting an extension of the body trough, a cover member for closing said trough and having an upturned end for closing said extension and leaving an opening at the end of said extension, a hood for closing said opening and fitting around said extension and upturned end, and electrical connections through said hood to said element, said connections including a thermostatic blade and cooperating blade supported on said body in said groove independent of said hood and having contacts located remote from the body on the ends of the blade extending through said opening into said hood whereby the contacts are accessible by removing said hood. 10 15

2. A curling iron comprising a pair of levers having a pivot connection, a hollow body secured to one of said pair of levers and having an electrical heating element therein and hair-engaging transverse ribs on one surface thereof, an angular extension on said body through which electrical connections pass to said heating element, a slider positioned at the opposite surface thereof and having hair-engaging teeth at its edges, said teeth being spaced from said body, said slider having an open ended slot through which said extension passes whereby to guide said slider, handle means on at least one of said pair of levers, means for moving said slider including a third lever pivoted to one of said pair of levers on an axis parallel to that of said pivot connection, and a pair of spaced tongs rigidly mounted on the other of said pair of levers for movement therewith to and from positions between said body and teeth.

3. A curling iron comprising a handle and a hollow body having an electrical heating element 40 therein and hair-engaging transverse ribs on one surface thereof, a slider positioned at the opposite surface thereof and having hair-engaging teeth at its edges, said teeth being spaced from said body, means for moving said slider, a pair of 45 tongs mounted for pivoting to and from positions between said body and teeth, a hollow extension at the handle end of the body directed away from said one surface, a thermostatic device including a thermostat blade, and a cooperating blade 50 mounted on said body and positioned in said extension and projecting beyond said extension, said blades having contacts at their projecting ends remote from said ribs, a hood covering said ends, a connection from one said blade to the 55 element, and electrical supply connections passing through said hood to one said blade and said element.

MAURICE F. FITZGERALD
